STITCHER MECHANISM

Nels A. Anderson, Stockton, Calif., assignor to
Fibreboard Products Inc., San Francisco, Calif.,
a corporation of Delaware

Original application January 29, 1940, Serial No.
316,170. Divided and this application February
21, 1941, Serial No. 379,992

4 Claims. (Cl. 1—11)

This is a division of my copending application, Serial No. 316,170 filed January 29, 1940.

My invention relates to mechanisms for stitching or stapling sheet material; and more particularly to a safety device for such mechanisms.

The broad object of my invention is to provide a device for stopping a stitcher after a predetermined number of stitches have been made to prevent injury to the stitcher head in event a blank becomes jammed in the mechanism.

Another object is to provide a safety device of the character described having a changeable control member for determining the number of stitches made before the stitcher is stopped.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a side elevational view of a stitcher mechanism with which my safety device is associated.

Figure 2 is a fragmentary elevational view showing the safety device. This device is mounted on the back of the stitcher housing relative to the side shown in Figure 1.

Figure 3 is a detail sectional view, taken in a plane indicated by line 3—3 of Figure 2, showing the safety device and its operative connection with the drive shaft of the stitcher.

In terms of broad inclusion, my improvements comprise a stitcher, and safety means timed with the stitcher for stopping the latter after a predetermined number of stitches have been made. The safety device preferably includes a changeable control member for determining the number of stitches made before the stitcher is stopped.

In greater detail, and referring to the drawing, my improvements are shown in conjunction with a machine for stitching a folded blank, such as disclosed in my above mentioned application. The machine includes a pair of suitably driven feed rolls 2 mounted on frame 3 and arranged to advance a folded blank between stapling head 4 and anvil 5 of the stitching mechanism. After leaving rolls 2 a pusher foot 6 actuated through suitable linkage 7 engages the trailing edges of the blank and pushes the latter against a trip 8. This trip is an element commonly associated with stitcher mechanisms and moves forwardly under the pressure of the advancing blank to start the stitcher, after which the trip is de-

pressed to clear the blank. Since trip 8 offers some resistance to movement the blank is subjected to a certain amount of edgewise compression, sufficient to true up the edges and square the fold.

Stapling head 4 and the associated trip 8 of the stitching mechanism may comprise parts of the well known "Latham" stitcher. Other parts of the Latham stitcher are also preferably employed, such as trigger 9, stitch spacing feed rolls 11 and discharge rolls 12. In accordance with the usual operation of a stitcher of this kind, the advancing blank first depresses trigger 9 which conditions the mechanism for operation, and then pushes trip 8 which engages a clutch (not shown) to start operation of the stapling head. Other mechanism of the stitcher then comes into play to rock an arm 13 and lower the upper stitch spacing feed roll 11 against the blank. These rolls are driven intermittently to advance the blank between stitches. After the trailing edge of the blank rides off trigger 9 the stapling head stops and arm 13 is rocked to lower upper discharge roll 12 against the stitched blank and deliver it from the machine.

In somewhat greater detail, Figures 2 and 3 show stapling head 4, trigger 9, latch arm 14, stapling head shaft 16, cam 17 and control lever 18, all of which are standard parts of the Latham stitcher. The view shown in Figure 3 is taken from the opposite side of the machine from that shown in Figure 1, so the path of the blank is reversed as indicated by arrow 19. When trigger 9 is depressed by a blank it causes latch arm 14 to move against the tension of spring 21 and bear against roller 22 of lever 18. Subsequent movement of trip 8 by the blank then starts the stapling head, one stitch being made for each revolution of its shaft 16. Upon rotation of shaft 16 the cam 17 depresses lever 18 and notch 23 of latch arm 14 engages over the lever roller to hold it down. Depression of lever 18 keeps the stapling head in operation and brings other mechanism (not shown) into play to lower the stitch spacing roll 11 against the blank. When the trailing edge of the blank rides off trigger 9 the latter retracts latch arm 14 to release lever 18, which stops the stapling head and causes discharge roll 12 to be lowered against the blank.

These parts of the Latham stitcher and the operation thereof are well known to those skilled in the art. It is also known that if a blank becomes jammed in the machine so as to hold trigger 9 down, the stapling head continues to drive staples in the same place, causing damage to

the head. To avoid this damage I provide a safety device to automatically stop the head after a predetermined number of staples have been driven.

The safety device to which my present invention particularly relates comprises an arm 24 freely pivoted on a shaft 25 journaled in a bracket 26 mounted on the housing of stitcher head 4. A spring 27 normally urges roller 28 of arm 24 into engagement with cam 17. At one end of shaft 25 is fixed a ratchet wheel 29 engaged by a pawl 30 carried by arm 24. A changeable control element or cam plate 31 is removably secured to a side of the ratchet by studs 32, and has a series of peripheral lobes 33 adapted to engage a catch 34 fixed on latch arm 14 at the arm pivot 35. By this arrangement latch arm 14 swings back to release arm 18 from notch 23 when a lobe rides under the catch, thereby stopping the stapling head. A suitable brake 36 frictionally engaging the other end of shaft 25 prevents ratchet 29 from overrunning.

In the operation of this device, arm 24 is oscillated by cam 17 and cam plate 31 is thereby turned through an arc defined by one ratchet tooth for each revolution of shaft 16. Thus, the distance between lobes 33 limits the number of stitches that can be made before the stapling head is stopped, should a blank become stuck in the mechanism; it being understood from the above explanation that the safety device operates to stop the stitching head independently of control finger 9. With the twelve lobed cam shown in Figure 3 the stapling head will be stopped after five staples have been driven. By replacing the changeable cam plate with one of the same diameter but having a different number of lobes, the

stapling head may be stopped after a greater or less number of stitches, depending upon the spacing between the lobes.

I claim:

1. In a blank stitching machine, a stitcher, means engageable with the blank for starting and stopping the stitcher, and safety means operating in time with the stitcher and independently of said means for stopping the stitcher.

2. In a blank stitching machine, a stitcher having a shaft, means including a lever movable from extended to retracted position for stopping the stitcher, a timing cam on the stitcher shaft for extending the lever, a latch for holding the lever extended, a control cam engageable with the latch for releasing said lever, and means actuated by the timing cam for moving the control cam.

3. In a blank stitching machine, a stitcher having a shaft, means including a lever movable from extended to retracted position for stopping the stitcher, a timing cam on the stitcher shaft for extending the lever, a latch for holding the lever extended, a control cam engageable with the latch for releasing said lever, and means including a ratchet actuated by the timing cam for moving the control cam.

4. In a blank stitching machine, a stitcher having a shaft, means including a lever movable from extended to retracted position for stopping the stitcher, a timing cam on the stitcher shaft for extending the lever, a latch for holding the lever extended, a control cam having a plurality of spaced lobes engageable with the latch for releasing said lever, and means actuated by the timing cam for moving the control cam.

NELS A. ANDERSON.
